CLAIM

The ornamental design for a module for a smart watch band, as shown and described.

DESCRIPTION

FIG. 1 is a right side elevational view of a module for a smart watch band;

FIG. 2 is a front elevational view thereof;

FIG. 3 is a bottom plan view thereof;

FIG. 4 is a top plan view thereof;

FIG. 5 is a back elevational view thereof;

FIG. 6 is a top, back, left side perspective view thereof;

FIG. 7 is a left side elevational view, shown side-by-side with a smart watch band with which the module may be integrated; and,

FIG. 8 is top, back, left side perspective view, shown aligned with a smart watch band with which the module may be integrated.

The broken line showing of the smart watch band in FIGS. 7 and 8 illustrate environment and form no part of the claimed design.

The remaining broken lines shown in the drawings depict portions of the module for a smart watch band and form no part of the claimed design.
